UNITED STATES PATENT OFFICE.

CHARLES E. BURNAP, OF CHICAGO, ILLINOIS; SARAH BURNAP, ADMINISTRATRIX OF SAID CHARLES E. BURNAP, DECEASED, ASSIGNOR TO THE C. F. PEASE COMPANY, OF CHICAGO, ILLINOIS, A CORPORATION OF ILLINOIS.

DRAWING-PEN.

1,384,232.

Specification of Letters Patent. Patented July 12, 1921.

Application filed July 29, 1913, Serial No. 781,711. Renewed December 9, 1920. Serial No. 429,602.

To all whom it may concern:

Be it known that I, CHARLES E. BURNAP, a citizen of the United States, residing at Chicago, in the county of Cook and State of Illinois, have invented certain new and useful Improvements in Drawing-Pens, of which the following is a specification.

This invention relates to drawing pens and has for its object the combination in a single instrument of a ruling pen and a quill pen or common writing pen.

Heretofore draftsmen have found it necessary to use the common pen and ruling pen alternately in various parts of a drawing particularly when the drawing is nearing completion. Many parts of a mechanical drawing must be made with a common quill pen and during the time of doing this the ruling pen must be laid down. While not in use the ink in the ruling pen will become dry and hard. Before the ruling pen can be used again the dry ink must be wiped out and the pen refilled. In like manner the common pen is laid down and the ink is drying while the ruling pen is in use. It must also be wiped and refilled when again taken up. This constant wiping and refilling of the pens results in a serious consumption of time. In fact when a draftsman is approaching the end of a drawing and is finishing various odds and ends in his work, the time lost in wiping and filling his pens amounts to more than that actually devoted to his drawing.

In the present practice when a draftsman finds it necessary to change pens he first must lay down the pen he is using, pick up the other pen, pick up a cloth and wipe out the partially dried ink, remove the cork from the ink bottle, deposit a quantity of ink in the pen, replace the cork in the bottle, and shift the pen from one hand to the other, before he can continue with his work on the drawing. This procedure is repeated many times and in many cases the accumulated loss of time amounts to hours.

The object of the device herein described is to save this time. As will be seen an instrument is provided in which a common quill pen may be instantly moved into posi-

tion for use when wanted. When not in use it is as quickly moved out of the way. The instrument may then be used as a ruling pen, in every respect as well as though the quill pen were not attached.

An important consideration in connection with this device is the fact that the same supply of ink is used by both pens. The point of the quill pen is constantly immersed in the ink of the ruling pen. When one pen is filled the other is filled also. When converting the tool from one form to the other no attention to the ink is necessary.

Other objects and advantages of this device will become apparent in the following detailed description when taken in connection with the drawings, in which—

Figure 1 is a side elevation;

Fig. 2 is an elevation at right angles to Fig. 1;

Fig. 3 is a cross section on the line 3—3 of Fig. 2;

Fig. 4 is a cross section on the line 4—4 of Fig. 2;

Fig. 5 is a view of the blank from which the quill pen holder is made;

Fig. 6 is a perspective view of the quill pen holder;

Fig. 7 is a view of a modified form;

Fig. 8 is a view at right angles to Fig. 7;

Fig. 9 is a perspective view of the ruling pen showing the form of one of the blades;

Fig. 10 is a perspective view of the writing pen holding clip; and

Fig. 11 is a perspective view of the writing pen.

It will be seen that the device comprises the usual type of ruling pen having the adjustable blades or nibs 10 and 11, between which the common quill or writing pen 12 is placed. The quill pen is carried by a sliding holder 13 by which it may be adjusted instantly to a position in which its point projects beyond the ends of the blades of the ruling pen; or it may be withdrawn to a position entirely within them.

The holder 13 is provided with a forked end comprising three tongues 14, 15 and 16. The body of the pen 12 is inserted between the tongues in the manner clearly shown in

the drawings particularly in Fig. 3. The curved body of the pen is inserted in the narrow slots between the tongues and is securely held therein by friction and by the 5 clamping effect of the elastic tongues.

The opposite end of the holder is folded over to a position adjacent the pen holding end, the blank shown in Fig. 5 being bent at the point 18, Fig. 2. This form gives it an 10 elastic property which causes it to press outwardly against the inner faces of the ruling pen blades. The friction thus caused insures the holder being firmly held in position between the blades.

15 The holder is provided with lateral wings 19 and 20 which are folded to a position at right angles to the body of the holder. These wings are adapted to bear upon the lateral edges of one of the blades 10. For 20 this reason the blade is made straight and its edges parallel to serve as a guide for the wings and to cause the holder to be centrally held and guided longitudinally from one position to the other.

25 The wings are made large and flat to serve also as means for enabling the user to push the holder from one position to the other. These flat surfaces also receive the pressure of the fingers of the hand when the pen is 30 being held and used.

In order to retain the holder at either end of its movement, an elastic tongue 21 is provided having an inwardly bent end 22 which is adapted to snap into the notches 23 and 35 24 in the blade 10. These notches have sloping sides, thereby permitting the holder to be dislodged from either of its positions by a moderate endwise pressure.

The upper end 25 of the holder is given 40 a slight inward bend to cause it to bear upon the back of the pen 12 and more firmly hold it. For the sake of clearness in the drawing the points of the ruling pen are shown widely separated. The end 25 of the holder 45 is then not in contact with the back of the quill pen.

Slots 26 and 27 in the two arms of the holder allow the screw 28 to pass through them without interference.

50 The tongue 16 of the holder is outwardly bent at its end 29 to bear upon the blade 10 and thereby keep the quill pen spaced from said blade. The two bent ends 25 and 29 co-operate to hold the quill pen in a central position between the blades of the ruling pen.

In Figs. 7 to 11, inclusive, I have illustrated a modified form of my invention in which the writing pen holder 30 is made 60 from a single leaf of metal having a curved or bowed form which lies between the blades of the ruling pen and in yieldable frictional contact with both said blades. The forward portion of the holder is provided with inwardly and upwardly curved lugs 31, 32 for

engaging and holding the writing pen 33. The lugs 31 have upward extensions 34 which bear upon the upper blade 35 of the ruling pen in order that the blades of said pen may be wedged apart in advance of the 70 writing pen when the latter is being pushed outwardly to its operative position.

The downwardly projecting lugs 36 bear upon the lateral surfaces or edges 37 of the lower blade of the ruling pen and serve to 75 guide the writing pen longitudinally and to hold it firmly against lateral movement. Similar lugs 38 at the rear or inner end of the holder also bear upon the lower blade. The lower edges of the lugs 38 are beveled 80 to facilitate swinging of the holder to an angular position with relation to the ruling pen for cleaning purposes. Such a position is indicated in dotted lines in Fig. 7.

The lugs 39 project laterally to permit the 85 user to easily push the holder from one position to the other with his fingers. These lugs may have any other position on the holder, such for example, as that shown in dotted lines at 40.

90 The middle portion of the holder is bowed or curved at 41 to bear upon the upper blade. This curvature is sufficient to produce the desired frictional contact with the blades. The metal is of such a thickness and elastic 95 quality as will produce the desired resistance to movement.

At the extreme inner end of the holder I have provided a small lug 42 which bears directly upon the lower blade and which 100 drops into notches 43 and 44 at the extremities of the holder's movement. By this means the holder is held firmly in either position against accidental displacement. The operator can dislodge said lug from either of 105 said notches, however, by exerting a moderate force upon the holder.

The holder can be swung to an angle with the ruling pen, for cleaning, by loosening the screw 45 sufficiently to permit the lugs 110 36 and 38 to be raised free of the lateral edges of the lower blade.

115 The manner of using the instrument will be obvious. When it is desired to use the quill pen it is only necessary to push it downwardly to its lower position by means of the wings 20 and 21, or 39. These wings are in a very convenient position for that purpose. The inventor of the instrument has found that by placing the end of his 120 forefinger upon the head of the screw 28 he can more conveniently move the ruling pen than the quill pen. The ruling pen may be moved up and down while holding the quill pen holder firmly by the thumb and second 125 finger. The thumb and second finger may be held in constant contact with the wings 20 and 21 or 39 while the forefinger manipulates the instrument.

130 Most draftsmen, however, will probably

find it more convenient to move the quill pen from one position to the other by the fingers of the left hand while the ruling pen is held in the right hand. Draftsmen always have 5 their left hands resting upon the drawing board in close relation to the work they are doing. It therefore requires no appreciable time to grasp the quill pen holder with the thumb and forefinger of the left hand and 10 push it upwardly or downwardly.

When pushing the quill pen forward to writing position it is not necessary to first open the ruling pen blades for the reason that the quill pen holder wedges them apart 15 in advance of the pen.

In case it is desired to clean the pens it is only necessary to open the ruling pen sufficiently wide to permit the quill pen and holder to be swung about the screw as a 20 pivot to an angular position. They are both then accessible for cleaning. The quill pen holder may be moved forward before it is swung around. Obviously, by removing the screw the quill pen and holder may be 25 removed altogether.

It will be found that partly dried ink can be loosened in either pen and made to flow, by moving the quill pen, even after it has been lying idle for several minutes.

30 A further advantage will be found in the fact that the writing pen may be dipped into the ink when filling in the usual manner of using all writing pens. This obviates the necessity of inserting a quill full of ink between the nibs of the ruling pen. The writing pen can be moved from one position to the other so quickly that it will be found to save time by filling the ruling pen in this manner.

40 While I have described more or less precisely the details of construction, I do not wish to be understood as limiting myself thereto, as I contemplate changes in form and the proportion of parts and the substitution of equivalents as circumstances may suggest or render expedient without departing from the spirit of my invention.

I claim:

1. In an instrument of the class described, 50 the combination with a pen having an ink holding portion, of a second pen, means for supporting said second pen in the ink holding portion of the first pen, and means for relatively moving said pens to present either 55 one in position for use.

2. In an instrument of the class described, 60 the combination with a ruling pen comprising two nibs adapted to hold a filling of ink between them, a second pen, means for connecting the second pen with the ruling pen in position to be fed from the filling of ink 65 between the nibs of the ruling pen, and means for moving said second pen relatively to the ruling pen to present either pen 65 in position for use.

3. In an instrument of the character described, a ruling pen comprising two nibs adapted to hold a filling of ink between them, and a second pen attached to said ruling pen between said nibs and movable 70 with relation thereto into and out of operative position.

4. In an instrument of the character described, a ruling pen comprising two nibs adapted to hold a filling of ink between 75 them, and a second pen attached to said ruling pen and movable with relation thereto into and out of operative position, the point of said second named pen being constantly immersed in the ink held by said ruling pen. 80

5. In an instrument of the class described, the combination with a ruling pen comprising two nibs, of a screw extending through said nibs for relatively adjusting them, a second pen, a holder for said second pen mounted between the nibs of the ruling pen and having an elongated slot through which said screw extends, and means for moving said holder relatively to the nibs of the ruling pen to project said second pen beyond the 90 ruling pen, or to withdraw said second pen within the nibs of said ruling pen. 85

6. In an instrument of the class described, the combination with a ruling pen comprising two nibs, of a screw extending through 95 said nibs for relatively adjusting them, a second pen, a holder for said second pen mounted between the nibs of the ruling pen and having an elongated slot through which said screw extends, means for moving said 100 holder relatively to the nibs of the ruling pen to project said second pen beyond the ruling pen, or to withdraw said second pen within the nibs of said ruling pen, and guiding means on said holder movably engaging one of the nibs of the ruling pen to support said second pen in longitudinal alignment with the ruling pen or permit said second pen to be swung laterally to one side of the ruling pen. 105

7. In an instrument of the class described, a ruling pen having a pair of blades, a second pen, and a holder for said second pen disposed between said blades and slidable toward the points of said blades, said holder 115 forcing said blades apart when said second pen is being moved to operative position.

8. In an instrument of the class described, a ruling pen having a pair of blades, a second pen, and a holder for said second pen 120 disposed between said blades and slidable toward the points of said blades, said holder forcing said blades apart when said second pen is being moved to operative position, the frictional engagement of said holder and 125 said blades serving to retain said second pen in operative position.

9. A instrument of the class described comprising two pens mounted for alternate use, one of said pens being supplied with 130

ink from the ink held by the other pen, and means for relatively moving said pens to present either of them in position for use.

10. An instrument of the class described comprising two pens each formed to hold ink by capillary attraction, one pen being supplied with ink from the ink held by the other.

11. An instrument of the class described comprising two pens, and means for effecting a relative movement of said pens to

present either of them in position for use, the movement of one of said pens taking place along an axis passing through the point of the other pen.

15

In testimony whereof, I have subscribed my name.

CHARLES E. BURNAP.
